[57] CLAIM

The ornamental design for a cushion unit, as shown and described.

DESCRIPTION

FIG. 1 is a top, front, and left side perspective view of a cushion unit showing our new design;
FIG. 2 is a top plan view thereof;
FIG. 3 is a bottom plan view thereof;
FIG. 4 is a front elevational view thereof;
FIG. 5 is a rear elevational view thereof; and,
FIG. 6 is a right side elevational view thereof, the left side being a mirror image of that shown.

FIG.1

FIG.2

FIG.3
